PAPER DELIVERING DEVICE

David G. Bernard, Chicago, Ill., assignor, by
mesne assignments, to Franklin W. Kohler,
Chicago, Ill.

Application January 16, 1932. Serial No. 587,050

9 Claims. (Cl. 242—58)

This invention relates to paper delivering devices particularly adapted to deliver paper to printing presses and the like, and has for its object to provide a new and improved device of 5 this description.

In the operation of printing presses at the present day, the paper for the newspapers is wound into rolls and these rolls are supported in proximity to the press and the paper delivered 10 to the press and formed into the newspapers. The present presses are run at a very high speed and it has been heretofore necessary to slow down the presses when the delivery of the paper to the press was changed from one roll to 15 another. One object of the present invention is to provide means for preventing this and for permitting the transfer of the delivery of the paper from one roll to another while the press is running at high speed.

20 The invention has further objects which are more particularly pointed out in the accompanying description.

Referring now to the drawings, Fig. 1 is a side elevation of one form of device embodying the 25 invention;

Fig. 2 is a view of the device shown in Fig. 1 as seen along the line 2—2;

Fig. 3 is an enlarged sectional view taken on line 3—3 of Fig. 2;

30 Fig. 4 is an enlarged sectional view taken on line 4—4 of Fig. 2;

Fig. 5 is an enlarged sectional view taken on line 5—5 of Fig. 1;

Fig. 6 is an enlarged view taken on line 6—6 35 of Fig. 1;

Fig. 7 is an enlarged sectional view taken on line 7—7 of Fig. 6;

Fig. 8 is a diagrammatic view showing the parts 40 when the paper is being delivered from the expiring roll before it is exhausted;

Fig. 9 is a similar view when the expiring roll is about exhausted and preparation is being made to connect the web of the new roll with the web of the expiring roll;

45 Fig. 10 is a similar view when the parts are in position to make this connection;

Fig. 11 is a similar view after the connection has been made between the web of the new roll and the web of the expiring roll.

50 Like numerals refer to like parts throughout the several figures.

Referring now to the drawings, wherein I have shown one form of construction embodying the invention, there is illustrated a roll supporting 55 device for supporting the rolls of paper, which in

this instance is indicated as a reel having the arms 1 between which the rolls of paper 2, 3 and 4 are received. Any suitable means is provided for rotating these arms to bring the new roll into proper position. As herein shown the arms are 60 connected with a shaft 5 which is driven by a motor 6 through a gear 7. The shaft is mounted upon the pedestals 8 or it may be supported in any desired manner. In proximity to the rolls of paper are a series of belts 9 spaced apart. Each 65 of these belts passes around a series of direction changing devices. In the particular construction shown each belt passes around the direction changing devices 10, 11, 12, 13 and 14. The direction changing devices 10 and 11 are located above 70 the roll supporting device, and the direction changing devices 13 and 14 are preferably connected with the floor, one of them being preferably below or in proximity to the bottom of the roll support. The direction changing device 12 75 for each belt is arranged in some manner to keep the belt taut. In the particular construction shown this direction changing device is illustrated as a pulley rotatably mounted in a carrier 15, slidably mounted on rods 16 which are suitably 80 supported in position as by being connected to the supports 17 and 18. These supports 17 and 18 are supported in any desired manner as by means of the brackets 19. These carriers 15 are weighted and are made sufficiently heavy to move 85 the direction changing devices 12 as the roll of paper decreases in size so as to keep the belts taut and in proper contact with the roll of paper.

The web of the new roll 3 is provided with an adhesive 20 for the purpose of connecting it with 90 the web of the expiring roll. A pressure device 21 is located in proper position to press the web of the expiring roll against the web of the new roll with sufficient pressure to cause the portion of the web of the new roll with adhesive thereon to adhere to the web 22 of the expiring roll. This pressure device 21 may be of any suitable form. For purposes of illustration I have shown it as consisting of a roller mounted in bearings 23 which are slidably mounted in guides 24, the 95 bearings preferably being provided with springs 25 and 26 normally pressing it toward the roll 3. An adjusting device 27 is associated with these bearings so as to control their position and hence the position of the roller and the pressure it applies.

The belts 9, as herein shown, are driven at the desired speed and the portion of the belts which contact with the roll of paper are moving downwardly. The adhesive 20 is placed between the 105 110

belts 9 so that these belts will not engage it. When the expiring roll is about exhausted it is moved away from the belt so that the web 22 engages the pressure device 21 and the new roll 3 is moved into contact with the belts and brought up to the desired speed, and when at the desired speed the new roll 3 is moved into contact with the web running over the pressure device 21, and then as the adhesive 20 comes around it will engage the web 22 of the expiring roll, thereby connecting the web of the new roll with the web of the expiring roll. When the belts 9 are run at the same speed as the press, or at a speed only slightly differing from that of the press, it will be seen that the roll of paper 3 is brought into substantially the same speed as the web 22 being delivered to the press, and that this flying paster or connection between the web of the expiring roll and the web of the new roll may be made while the press is running at full speed.

In delivering paper to printing presses, for example, it is desirable under certain conditions to drive the belts 9 at a speed somewhat slower than the speed of the press so that the belts will have a retarding effect on the roll to insure the tautness of the paper being delivered to the press. In cases where the difference in the speed of the belts and the speed of the press is such that there might be a slip between the web of the expiring roll and the adhesive on the web of the new roll when the connection is being made, I provide means for compensating for this. Under such conditions I may, for example, speed up the belts 9 just before the adhesive 20 on the new roll is brought into contact with the web of the expiring roll so as to bring the two webs at substantially the same speed at the time the connection is made. In the drawings I have shown one means for this purpose. I may, for example, arrange the direction changing devices 10 and 11 so that one of them is larger in diameter than the other. For example, the direction changing device 10 may be made large in diameter than the direction changing device 11. I may then provide means for driving the belts normally through the smaller direction changing device 11, the connection to the driving mechanism being such that the belts will then be driven at the desired speed less than the speed of the press.

When it is desired to make the connection between the web of the expiring roll and the web of the new roll, the drive is changed to the direction changing device 10, and since this is larger in diameter than the direction changing device 11, the belt 9 will be speeded up the desired amount so that the new roll 3 will be brought to the proper speed before the connection is made.

In the drawings I have shown a driving shaft 28, which may be a shaft on the press or may derive its power from any other source. This shaft has a driving connection 29 with a shaft 30. The shaft 30 is provided with the beveled gears 31 and 32. The beveled gear 31 engages the beveled gear 33 which normally rotates freely on the shaft 34. The gear 33 has a clutch member 35 adapted to be engaged by the clutch member 36, slideable on the shaft 34 but connected therewith so as to rotate with the shaft. The gear 32 is connected with the gear 37 which rotates freely on the shaft 38 but which has the clutch member 39 adapted to be engaged by the clutch member 40 slideable on the shaft 38 but rotating therewith. The clutch members 39 and 40 are controlled by the controlling member 41 pivoted at 42. This member may be controlled by hand if desired,

or by any other means. As herein shown I have provided electrical means for moving the controlling member. An electromagnetic device 43 is provided with an armature or core 44 connected with the controlling device 41 so as to actuate it. A retracting spring 45 is also connected with the controlling device. The electromagnetic device 43 is connected by the conductors 46 with the electric circuit 47 through a switch 48. When the switch is moved to its closed position, current passes through the electromagnetic device and moves the controlling element 41 to disconnect the clutch element 36 with the clutch element 35, and connect the clutch element 40 with the clutch element 39, thereby changing the drive from the direction changing device 11 to the direction changing device 10. (See Fig. 6.) Since the direction changing device 10 is larger in diameter than the direction changing device 11, it will be seen that the belts, with the same speed as the shaft 30, will then be speeded up and the parts are so arranged and adjusted to secure the desired speed. When the roll 3 has been brought to the desired speed and the paster made, the switch 48 is opened and the spring 45 moves the controlling element 41 so as to again connect the shaft 30 with the direction changing device 11. The apparatus is normally run when the parts are in this condition. It is of course evident that this speed changing device is only used under conditions where it is necessary and may be omitted when the difference in speed of the belts 9 and the press is not such as to require it to make a proper paster or connection between the expiring roll and the new roll.

I have shown in Fig. 7 a detail of one of the beveled gears, showing an arrangement whereby the gear 37 may rotate freely on the shaft 38. In this construction the end of the gear is recessed and a plate 49 is attached to the end of the shaft by a fastening device 50 which prevents the gear from coming off of the end of the shaft. The other end of the gear is recessed and a collar 51 in this recess is connected with the shaft 38 by the fastening device 52. It will thus be seen that the gear can rotate freely on the shaft, and when the clutch member 40 is connected with the clutch member 39, the gear is connected with the shaft 38 so as to rotate it. The other gear 33 is similarly arranged.

I have shown diagrammatically a severing device 53 for severing the web from the expiring roll after it has been connected with the web of the new roll.

The use and operation of my invention are as follows:

When the device is in use the rolls of paper are placed upon the roll or support, and one of these rolls, as for example the roll 2, is moved in contact with the belts and the paper is delivered to the press. This position of the parts is shown in Fig. 8.

When the roll 2 is nearly exhausted the roll supporting device is moved so as to bring the roll 3 into contact with the belts 9, as shown in Fig. 9. This also brings the web 22 of the expiring roll into contact with the pressure device 21 and the parts are in the position shown in Fig. 9. The contact of the belts 9 with the roll 3 of paper causes said roll to be set in motion and it is rotated in the direction of the arrow until it attains the proper speed. The roll support is then moved further to bring the roll 3 into contact with the web 22 and press it against the web of the new roll so as to connect the web

- of the new roll with the web of the old roll and change the feed to the web of the new roll 3. This position is shown in Fig. 10. The web 22 is then severed and the paper is delivered to the 5 press from the new roll 3, all of this being done while the press is running at its high speed and without slowing it down. I have shown diagrammatically in Fig. 11 a severing device 53 for severing the web 22 of the expiring roll.
- 10 If the difference in speed of the belts 9 and the web of paper being delivered to the press is sufficiently great to make it difficult or impossible to make the connection between the web of the expiring roll and the web of the new 15 roll, when the new roll is brought up to the high speed the belt will give it, then when it is desired to change the feed from one roll to the other, the belt 9 is speeded up by energizing the electromagnetic device 43 by closing the switch 48.
- 20 This changes the drive from the shaft 34 to the shaft 38 and direction changing device 10. The belt is then speeded up to the desired speed and this causes the new roll 3 to be rotated at the desired speed so that when it is brought into 25 contact with the web 22 of the expiring roll, the end of the web on the new roll having adhesive will be pressed against the expiring web 22 by the pressure device 21 and the two webs connected together. It will be seen that by means 30 of this device the web of the new roll may be connected to the web of the expiring roll while the press is running at its full speed. It will further be seen that as one roll of paper runs out so as to be nearly exhausted, the next roll 35 is then brought into action in the same manner as above described. A new roll is put in the place of the expired roll and the process is continued as long as desired so that it is unnecessary to stop the press or slow it down for the 40 purpose of changing the feed from one roll to another.
- I claim:
1. A paper delivering device comprising a plurality of separated belts, means for driving said 45 belts, a roll supporting device in proximity to the belts and carrying a plurality of rolls of paper, one roll of paper from which paper is being delivered being in contact with said belts while the paper is being delivered therefrom, a pressure 50 device separate from and at a distance from the belts, means for moving said roll support so as to move the roll from which paper is being delivered out of contact with said belts, and for moving a new roll into contact with said belts, the new roll 55 being brought up to speed by engagement with said belts, and for also moving said roll support, after the new roll has been brought up to speed, so as to bring it in contact with the web of the expiring roll so as to press said web against the 60 pressure device to cause the web of the new roll to adhere to the web of the expiring roll and change the feed to the new roll.
2. A paper delivering device comprising a plurality of separated belts, means for driving said 65 belts, a roll supporting device in proximity to the belts and carrying a plurality of rolls of paper, one roll of paper from which paper is being delivered being in contact with said belts while the paper is being delivered therefrom, a pressure 70 device separate from and at a distance from the belts, means for moving said roll support so as to move the roll from which paper is being delivered out of contact with said belts, and for moving a new roll into contact with said belts, the new roll 75 having adhesive on the end of its web at points between the belts, and for also moving said roll support, after the new roll has been brought up to speed, so as to bring it in contact with the web of the expiring roll so as to press said web against the pressure device to cause the web of the new roll to adhere to the web of the expiring roll and change the feed to the new roll.
3. A paper delivering device comprising a plurality of separated belts, means for driving said belts, a roll supporting device in proximity to the belts and carrying a plurality of rolls of paper, one roll of paper from which paper is being delivered being in contact with said belts, a pressure device separate from and at a distance from the belts, means for moving said roll support so as to move the roll from which paper is being delivered out of contact with said belts, and for moving a new roll into contact with said belts, the new roll having adhesive on the end of its web at points between the belts, and for also moving said roll support, after the new roll has been brought up to speed, so as to bring it in contact with the web of the expiring roll, so as to bring the speed of the periphery of the new roll up to substantially the speed of the web of the expiring roll.
4. A paper delivering device comprising a plurality of separated belts, a roll supporting device in proximity to the belts, and carrying a plurality of rolls adapted to be brought into contact with the belts, means for driving the belts so that the roll in contact therewith will be rotated, a pressure device separate from said belts and at a distance therefrom, means for moving said roll supporting device to move the expiring roll out of contact with the belts and bring the web thereof into contact with said pressure device and bring a new roll into contact with said belts, the new roll being brought up to speed by contact with said belts, the web of the new roll being provided with adhesive intermediate said belts, and also for further moving the new roll so as to bring the web thereof into contact with the web of the expiring roll, the new roll pressing the web of the expiring roll against the pressure device so as to cause adhesive on the web of the new roll to connect said web with the web of the expiring roll and change the feed to the new roll.
5. A paper delivering device comprising a belt, means for driving said belt, a roll supporting device in proximity to said belt, and carrying a plurality of rolls of paper adapted to be successively brought into contact with said belt while the paper is being delivered therefrom, means for utilizing the same belt for bringing the new roll of paper up to the speed of the web being delivered from the expiring roll, and a pressure device separate from said belt for pressing the web of the expiring roll and the new roll together to

connect them, the new roll having adhesive on the web to facilitate this connection.

5. A paper delivering device comprising a belt, means for driving said belt, a roll supporting device in proximity to said belt and carrying a plurality of rolls of paper, one roll from which paper is being delivered being in contact with said belt, means for moving said roll supporting device so as to disconnect from the belt the roll 10 from which paper is being delivered, and bring into contact with the same belt the new roll having adhesive on its web out of contact with said belt, the belt causing the new roll to be brought up to the speed of the web being delivered 15 from the first mentioned roll, and means, separate from the belt, brought into operation by the movement of the new roll for pressing the web of the new roll against the web of the roll from which paper is being delivered so as to connect 20 the web of the new roll with the web being delivered from the first mentioned roll.

6. A paper delivering device comprising a belt, means for driving said belt, a roll supporting device in proximity to said belt and carrying a plurality of rolls of paper thereon, one of said rolls, the expiring roll, being in contact with said belt, the web from said expiring roll leaving the roll on the opposite side thereof from the side engaged by said belt, means for moving said roll supporting device so as to disengage the expiring roll therefrom and bring the new roll into contact therewith, the belt engaging the new roll so as to cause it to rotate at the desired speed, the new roll having adhesive on the web thereof intermediate said belt, and for also moving said new roll, after it has been brought up to speed, into contact with the web of the expiring roll, so as to bring the speed of the periphery of the new roll up to substantially the speed of the web of the expiring roll.

50 7. A paper delivering device comprising a series

of separated belts, a roll supporting device in proximity thereto, having a plurality of rolls of paper thereon, one of said rolls, the expiring roll, being in contact with said belts, the web from said expiring roll leaving the roll on the opposite side thereof from the side engaged by said belts, means for moving said roll supporting device so as to disengage the expiring roll therefrom and bring the new roll into contact therewith, the belts engaging the new roll so as to cause it to rotate at the desired speed, the new roll having adhesive on the web thereof intermediate said belts, and for also moving said new roll, after it has been brought up to speed, into contact with the web of the expiring roll while it is in engagement with said pressure device, the movement of said new roll causing the web of the expiring roll to be pressed tightly against the adhesive on the web of the new roll so as to connect the web of the new roll with the web of the expiring roll, the web of the new roll then passing from the new roll on the side thereof opposite to the side in engagement with said belts and a speeding up device associated with said belts for speeding up the belts while the new roll is in contact therewith prior to its being brought into contact with the web of the expiring roll, so as to bring the speed of the periphery of the new roll up to substantially the speed of the web of the expiring roll.

8. A paper delivering device comprising a series of separated belts, a roll supporting device in proximity to said belts having a plurality of rolls of paper thereon, one of said rolls being in contact with said belts while the web of paper leading therefrom is being delivered to the point of use, the belts in contact with the roll and the web of paper delivered therefrom moving in opposite directions, means for moving a new roll of paper, which has adhesive applied to its web between said belts, into contact with the same belts when the first roll is reduced in diameter so as to bring said new roll up to speed, and simultaneously moving said first roll out of contact with said belts, and for also moving the new roll, after it has attained its speed, into contact with the web of the reduced roll and pressing the webs together to connect the web of the reduced roll with the web of the new roll.
